BUILDING CONSTRUCTION

Robert L. Davison, New York, N. Y.

Application December 16, 1941, Serial No. 423,142

5 Claims. (Cl. 20—4)

This invention relates to building construction, especially building construction of the type where component structural elements are prefabricated for immediate use in the field.

The invention is primarily concerned with framing structure in the form of lintels, sills, mullions, etc. for window frames, filler panels, and the like.

The presently disclosed construction constitutes an improvement in the prefabricated building constructions set forth in my U. S. Patent No. 2,235,811, issued March 25, 1941 and in my co-pending application for U. S. Patent, Serial No. 393,498, filed May 15, 1941, and has to do especially with the lintel, sill, and mullion elements of such building constructions. Accordingly, only the lintel, sill and mullion elements, and such additional structure of the building as a whole as is necessary to show the advantages effected by the present invention, are here illustrated.

My above mentioned patent sets forth the exterior walls of the building as made up of horizontal courses, preferably three courses for each story of the building, namely, a lower course made up of panel wall structural units, an upper course also made up of panel wall structural units, and an intermediate course made up of windows, or filler panels, or, usually, a well designed combination of the two. The lintel and sill elements extend peripherally of the building, substantially co-extensively with the respective wall courses, and serve to receive and position the windows and filler panels.

Pursuant to the present invention, the lintel and sill elements are arranged to not only receive and position window framing structures and filler panels, but are also arranged to tightly clamp the same into place so they become structural entities serving strengthening and stiffening purposes in combination with the associated structural elements of the building, without preventing interchange of such window frames and filler panels, or additions and reductions of one or the other, at a future time as desired.

To the above and other objects, as appear hereinafter, the lintel and sill elements are each formed of mutually co-acting longitudinal parts serving as clamp jaws, and are adjustably secured to one another by threaded connecting elements which are arranged to be rotated for cinching such longitudinal parts tightly against their associated window frame structures and filler panels.

An object of the invention, therefore, is to provide means whereby the windows and filler panels of a building construction of the type described

may be so bound into the construction as a whole as to contribute materially to the structural strength and rigidity of the building construction while providing for relatively simple and easy rearrangement of the associated windows and filler panels if and when desired.

Another object is to simplify the erection of the building structure, and the disassembly thereof as and when desired.

Further objects and features of the invention will be apparent from the following detail description of the preferred specific embodiments illustrated in the accompanying drawings.

In the drawings:

Fig. 1 represents a front perspective view of a building embodying the invention;

Fig. 2 is a fragmentary vertical section taken on line 2—2, Fig. 1, on an enlarged scale;

Fig. 3 is a fragmentary horizontal section taken on line 3—3, Fig. 1 and enlarged on a scale greater than that of Fig. 2;

Fig. 4 is a vertical section taken on the line 4—4, Fig. 1, enlarged on a scale greater than that of Fig. 3, and illustrating the lintel and sill construction in detail, the central portion of the filler panel being broken away for clarity;

Fig. 5 is a view similar to that of Fig. 4, but taken on line 5—5, Fig. 1, extending through a window frame;

Fig. 6 is a fragmentary horizontal section taken on line 6—6, Fig. 5, and illustrates in detail a mullion formed pursuant to the invention.

Fig. 7 is an exploded fragmentary view of the complementary elements of the sill or lintel; and

Fig. 8 is a fragmentary view in inside elevation, i. e. looking from right to left in Fig. 5.

In the building construction of Fig. 1, illustrated as a dwelling house, the wall construction comprises a lower course 10 of prefabricated panel wall units, an intermediate course 11 of filler panels and/or windows, and an upper course 12 of prefabricated panel wall units.

The individual panel wall units of the lower course 10 are indicated 13, the filler panel units and window frame units of the intermediate course 11 are indicated 14 and 15, respectively, and the panel wall units of the upper course 12 are indicated 16.

Columns or uprights provide the structural framework for the walls, see 17, Figs. 2 and 3, and the respective wall courses extend substantially peripherally therearound.

Defining the intermediate course 11 are peripherally extending lintel and sill assemblies, indicated generally 18 and 19, respectively, and extending vertically within such intermediate course

are mullions, indicated generally 19. These structural assemblies have characteristics peculiar to this invention, and, as a result, contribute advantageously to the construction as a whole.

The lintel and sill assemblies are desirably substantially mutually similar in construction, as illustrated, see particularly Figs. 4 and 5.

Referring now to Figs. 4, 5, 7 and 8, it is apparent that the lintel 17 comprises longitudinally extending jaw parts 20 and 21, respectively, separately formed, but mutually joined for clamping and unclamping action by reason of their threaded connecting elements 22, here shown as long, bolt-headed wood screws. Such connecting elements are spaced apart along the length of the lintel 17 at convenient intervals, and extend through suitable passages 23 which are pre-bored through the inside jaw part 21, see particularly Fig. 7. Their heads rest in a longitudinal channel 24, which desirably is common to all, and their threaded shanks bite into the outside jaw part 20 in the clamping operation, see especially Figs. 4 and 5. A socket wrench may be used to tighten or untighten each threaded connecting element 22, and the open channel 24 may be closed by a cap-strip 25, which desirably fits frictionally into place.

It is preferred to provide a washer 26 under the head of each threaded connecting element 22 as an aid in the cinching operation.

The longitudinally extending jaw parts 20 and 21 are each rabbeted longitudinally along the upper and lower margins of their respective jaw faces, as at 27, 28 and 29, 30, respectively, see Fig. 7, for providing upper and lower jaw portions. The remaining intermediately disposed rib portions 20a and 21a of the jaw parts 20 and 21, respectively, serve to divide the upper and lower jaw portions from each other, and to complete the formation of longitudinal receiving pockets thereat for receiving and seating longitudinal edge portions of associated wall units. The upper jaw portion of the lintel assembly receives and seats the lower longitudinal edge portions of panel wall units 16 of the upper wall course 12, while the lower jaw portion receives and seats the upper longitudinal edge portions of filler panels 14 and/or window frames 15 of the intermediate wall course 11.

To provide for positive gripping by the lintel, and tying in thereof, with the received wall units, the gripping faces of the upper and lower jaw portions are provided with penetrating members.

As illustrated, such penetrating members are of the form of double pointed pins 31, which may either be partially driven into the gripping faces of the jaw portions prior to assembly of the lintel, see Fig. 7, or suitably set intermediate such gripping faces and the opposing faces of the received wall units just prior to the closing of the jaws of the lintel, whereby such pins penetrate deeply, and preferably equally, into the jaw parts of the lintel and into the received wall units.

Weather-proofing material may be inserted at appropriate locations between the jaw faces and the opposing faces of the received wall units, e. g. see 32, Figs. 4 and 5.

The sill assembly is here shown as substantially similar in essential parts with the lintel assembly. The above description of the lintel assembly also applies to the sill assembly, and like parts are therefor indicated by like reference characters with a prime added thereto.

The mullion assemblies 19, see Figs. 6 and 8, advantageously embody a clamping principle

somewhat similar to that of the lintel and sill assemblies. Each mullion assembly comprises vertically extending jaw parts 35 and 36, separately formed, but mutually associated for clamping and unclamping action by threaded connecting elements. Here the threaded connecting elements are shown as relatively long wood screws 37 which pass through suitable bores provided at suitably spaced intervals along the length of the inner jaw part 36, and bite into the body of the outer jaw part 35.

The outer jaw part 35 is advantageously rabbeted along its length to provide, together with the clamping face of jaw part 36, a vertically extending receiving pocket 37, which serves to receive a lateral edge portion of a filler panel 14. The inner, vertically extending, edge face 35a of outer jaw part 35 is chamfered to provide a wedge-shaped opening 38 which extends vertically between the two jaw parts 35 and 36 and permits very tight clamping between such two jaw parts.

Washers 39 may be provided under the heads of screws 37 to ease the clamping movements of such screws and to protect the head-receiving depressions of the jaw part 36 against splintering.

Whereas this invention has been illustrated and described with reference to a preferred specific embodiment thereof, it should be clearly understood that various changes might be made in such preferred specific embodiment and that various other specific embodiments may be utilized by those skilled in the art without departing from the spirit and generic scope of the invention as set forth herein and in the appended claims.

I claim:

1. In building construction, structurally joining means comprising a pair of long jaw elements having jaw faces defining long receiving pocket means on mutually opposite sides thereof for receiving, and for clamping into position therewith, associated structure; and adjustable connecting elements joining said jaw elements at spaced locations along the lengths thereof and arranged for clamping said jaw elements together and for unclamping said jaw elements, one of said jaw elements providing a continuous outer window framing structure, and the other jaw element providing a continuous inner window framing structure.

2. In building construction, structurally joining means comprising a pair of long jaw elements having jaw faces defining long receiving pocket means on mutually opposite sides thereof for receiving, and for clamping into position therewith, associated structure; and adjustable connecting elements joining said jaw elements at spaced locations along the lengths thereof and arranged for clamping said jaw elements together and for unclamping said jaw elements, one of said jaw elements providing a continuous outer window sill structure and the other a continuous inner window sill structure.

3. In building construction, an adjustable joint comprising a pair of long jaw elements having jaw faces defining long receiving pocket means on either side thereof for receiving and clamping into place associated structure at right angles thereto, adjustable connecting elements joining said jaw elements at spaced locations along the lengths thereof and arranged for clamping said jaw elements together and for unclamping said jaw elements, means provided in one of said jaw

elements along its length thereof for receiving said adjustable connecting elements, and single means provided for covering said multiple adjustable connecting elements.

4. Building construction, comprising substantially horizontally extending courses of wall units including a lower course of prefabricated panel wall units, an intermediate course of window frames and filler panels, and an upper course of prefabricated panel wall units; substantially horizontally extending lintel structure disposed between the said intermediate course and the said upper course, being substantially coextensive therewith and tying the two together; and substantially horizontally extending window sill structure disposed between the said intermediate course and the said lower course, being substantially coextensive therewith and tying the two together, said lintel and said window sill structures each comprising pairs of relatively long jaw elements forming, between the component jaw elements thereof, long substantially horizontally extending upper and lower pockets for receiving edge portions of the units making up the said intermediate and the said upper and lower courses, respectively, and threaded adjustable connecting elements joining said component jaw elements of said pairs of jaw elements at spaced intervals along the lengths thereof and arranged for clamping said component jaw elements tightly about said received edge portions of the wall units and for unclamping said jaw elements.

5. Building construction, comprising substantially horizontally extending courses of wall units including a lower course of prefabricated panel

35

wall units, an intermediate course of window frames and filler panels, and an upper course of prefabricated panel wall units; substantially horizontally extending lintel structure disposed between the said intermediate course and the said upper course, being substantially coextensive therewith and tying the two together; and substantially horizontally extending window sill structure disposed between the said intermediate course and the said lower course, being substantially coextensive therewith and tying the two together, said lintel and said window sill structures each comprising pairs of relatively long jaw elements forming, between the component jaw elements thereof, long substantially horizontally extending upper and lower pockets for receiving edge portions of the units making up the said intermediate and the said upper and lower courses, respectively, threaded adjustable connecting elements joining said component jaw elements of said pairs of jaw elements at spaced intervals along the lengths thereof and arranged for clamping said component jaw elements tightly about said received edge portions of the wall units and for unclamping said jaw elements, and gripping elements disposed at the jaw faces of said component jaw elements, said gripping elements being anchored in said component jaw elements and in the received portions of the units of said intermediate, and upper and lower wall courses, respectively, for tying said units and said lintels and window sill structures rigidly together against twisting forces.
